(57) **CLAIM**

The ornamental design for a projector, as shown and described.

DESCRIPTION

FIG. 1 is a perspective view of a projector showing my new design;

FIG. 2 is another perspective view seen from the back side thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an enlarged, partial perspective view showing back

portion thereof, as designated by label 9 in FIG. 2;

FIG. 10 is a sectional view thereof along a line A-A, as

indicated in FIG. 7;

FIG. 11 is an enlarged, partial sectional view thereof as

designated by label 11 in FIG. 10; and,

FIG. 12 is an enlarged, partial sectional view showing a

projecting head thereof, as designated by label 12 in FIG. 10.

The broken lines are for illustrating unclaimed portions of

the projector or environmental structures, the broken lines

form no part of the claimed design.
